REFRIGERATION APPARATUS

Gregg F. Forsthoefel, Springfield, Mass., assignor
to Westinghouse Electric & Manufacturing
Company, East Pittsburgh, Pa., a corporation
of Pennsylvania

Application March 29, 1933, Serial No. 663,423

3 Claims. (Cl. 220—9)

My invention relates to the construction and method of assembling a cabinet, and specifically both to the provision of a thermal seal for connecting adjacent edges of inner and outer walls 5 of a cabinet construction and to a method of assembling the seal with respect to a cabinet.

My invention relates more particularly to a breaker strip or thermal seal for connecting inner and outer walls of a refrigerator cabinet and the like, about the door opening thereof, the thermal seal or breaker strip construction preferably comprising an inner or anchor member connected to an outer or facing member, the outer or facing member preferably being 10 made of non-hygroscopic material having low conductivity for heat. The inner or anchor member is connected to a flange provided on the inner wall and bounding the door opening with an autogenous joint consisting preferably of rubber 15 formed between the flange and the inner edge of the facing member, and the facing member overlaps and has its outer edge bearing against a flange formed on the outer wall and bounding the door opening, a space being provided between 20 the anchor member and the outer edge of the facing member to permit the entry therebetween of the latter flange. In assembling the cabinet, the thermal seal is connected to the inner wall and the latter is inserted in the outer wall in 25 such a manner that the flange on the outer wall enters the space formed between the anchor member and the outer edge of the facing member of the thermal seal, an inclined face provided on the anchor member and bounding said space 30 at one side preferably bearing against the inner edge of the outer wall flange to assure tight overlapping engagement of the facing member with the latter flange.

The inner cabinet wall, with the thermal seal 35 assembled thereon, is then disposed with relation to the outer cabinet wall in such a manner that the anchor and facing members, particularly the facing member, engage the outer wall, means being provided for forcing the inner wall member of the cabinet with the seal assembled thereon in such a direction that the anchor member of the seal is forced tightly against the outer wall facing member engaging the latter tightly.

It is, therefore, an object of my invention to 40 provide an effective and inexpensive thermal seal between spaced-apart wall members of a cabinet, such as a refrigerator cabinet.

It is another object of my invention to provide 45 a thermal seal for connecting spaced-apart wall members of a cabinet in which no fastening

means extend through exposed parts of the seal.

It is still another object of my invention to provide a novel and inexpensive method of assembling such a seal on a cabinet.

These and other objects are effected by my invention, as will be apparent from the following description and claims taken in accordance with the accompanying drawings, forming a part of this application, in which:

Fig. 1 is a sectional view of a cabinet construction showing one side thereof and part of the back, front and door illustrating a preferred embodiment of my invention.

Fig. 2 is an exploded view taken on a horizontal section of the cabinet, the heat insulation being deleted for the sake of clearness, and,

Fig. 3 is a sectional view taken on a vertical section of the cabinet parallel to the door opening.

Referring now to the drawings for a detailed description of my invention, numeral 1 designates a refrigerator cabinet comprising generally an outer wall 2, an inner wall or food liner 3 and heat insulation generally designated at 4 between the walls 2 and 3. The walls 2 and 3 are provided with a door opening 5, and a suitable door 6 is provided for closing the opening 5.

The cabinet 1 more specifically comprises a one piece outer shell 16 which forms vertical side walls 17 and a vertical front wall 18 in which the door opening 5 is formed. The edges of the front wall 18 are provided with inwardly extending flanges 19 at the door opening 5, the flat front portions 21 of the shell 16 forming marginal areas surrounding the door opening 5.

The cabinet 1 further comprises a bottom plate 22, and a top plate 23 which form, with the food liner 3 and insulation 4, an insulated food compartment 24 for supporting objects to be cooled. An opening 25 is provided in the food liner 3 and top plate 4 for the insertion of a cooling unit (not shown). A back plate 26 is fastened to the outer shell 16 by bolts 27 and forms the rear vertical wall of the cabinet 1. The outer shell 16 and back plate 26 extend above the top plate 23 and form a machinery compartment 27. A top 28 is provided for the machinery compartment 27.

The food liner 3 comprises a five-sided shell having flanges 29 turned toward each other at the door opening 5. An aperture 31 is provided in each flange 29 for a purpose hereinafter described.

The flanges 19 and 20 of wall members 2 and 3 respectively are spaced apart at the door open-

ing 5, as best shown in Fig. 1, and a thermal seal generally designated at 8 connects the wall members. In the embodiment of the invention illustrated, the thermal seal 8 comprises a wooden inner or anchor member 9 having a wedge-shaped portion 11 at one edge, an outer or facing member 12, preferably a flat strip of non-hygrosopic material such as a resinous condensate product, is fastened to the anchor member 9 at one side thereof, adjacent to the wedge side 11, by means of cement as shown at 13. The facing member 12 extends as far as the wedge-shaped portion 11 of the anchor member 9, as shown at 14, and extends past the anchor member 9 at the edge opposite to the wedge-shaped edge 11, as shown at 15.

The cabinet 1 is manufactured and assembled in the following manner: The outer shell 16 is stamped with its door opening 5 and flanges 19 surrounding the door opening, and is bent to form the front wall 18 and side walls 17. The bottom plate 22 is then preferably welded to the outer shell 16 as shown at 32. Blocks of solid insulation 33 are disposed on the plate 22 as shown in Fig. 3.

The thermal seal 8 is assembled on the food liner 3. The inner or anchor member 9 is fastened to the flange 29 by means of a wood screw 34 which pass through apertures 31 in the flange 29, the wedge 11 being at the edge of the securing member 9 opposite to the edge which is held to the flange 29. The outer or facing member 12 is cemented to the securing member 9 in a manner hereinbefore set forth. A joint 35 is formed between the end 15 of the strip 12 and the flange 29 of the food liner 3, which joint is made moisture-proof by the application of rubber 35 or the like in a molten state, after which it is allowed to harden and form an autogenous joint.

The food liner 3, with the thermal seal 9 assembled thereon is then disposed in the outer shell 16 either through the back thereof as shown in Fig. 2, or it may be inserted through the top, 45 and finally rests on the rigid insulation 33. Loose insulation 36 is packed between the side walls 17 of the outer shell 16, and the food liner 3. Blocks of rigid insulation 37 are placed in the back of the box and extend from the bottom 50 block insulation 33 to the top of the food liner 3. The back plate 26 is then forced into place and fastened by bolts 27. The rigid back insulation 37 is of sufficient width that the food liner 3 with the seal 9 assembled thereon will be pushed forwardly when the back plate 26 is forced into place. The wedge 11 engages one side of the flange 19 of the outer shell 16, while the strip 12 contacts tightly the other side of the flange 19, thus forming a moisture resistant joint. It 55 will be noted that the effect of the wedge 11 engaging the inner side of the flange 19 is to cause the outer edge of the facing member strip 12 to overlap and tightly engage the outer face of the flange 19, for, in assembling, the tendency would 60 be for the wedge action to tilt the thermal seal so as to obtain tight engagement of the facing member with the outer face of the flange.

Block insulation 39 is disposed on the top of the food liner 3 and the top plate 23 is fastened 65 by welding (not shown) to the outer shell 16. Strips 41 of heat insulating material connect the food liner 3 and the top plate 23 at the cooling unit opening 25. Legs 42 and the top 28 are added to complete the assembly.

From the foregoing, it will be apparent that I have provided a novel and inexpensive cabinet construction and method of assembling the same, including a thermal seal. As is well known, if moisture enters the insulation of a heat insulated cabinet, its heat restivity is materially decreased. It will be apparent, that by dispensing with mechanical connections between the exposed parts of the seal and the interior thereof and by providing an autogenous joint between the food liner and the breaker strip at the point where condensation of moisture is most likely to occur because of the difference in temperatures at this point, that the possibility of moisture entering the space between the outer shell and the food liner, and thereby affecting the insulation of the cabinet, is materially decreased.

While I have shown my invention in but one form, it will be obvious to those skilled in the art that it is not so limited, but is susceptible of various other changes and modifications without departing from the spirit thereof, and I desire, therefore, that only such limitations shall be placed thereupon as are imposed by the prior art or as are specifically set forth in the appended claims.

What I claim is:

1. A cabinet construction including inner and outer walls having flanges bounding a door opening, a thermal seal connected to the flange of the inner wall member and including a facing member having a sealed connection with respect to the flange on the inner wall member, said thermal seal having a wedge portion provided thereon for engagement with the flange of the outer wall member to cause the facing member of the seal to tightly engage said latter flange.

2. In a refrigerator cabinet including inner and outer walls having inner and outer flanges, respectively, bounding the door opening, breaker strip means providing a connection between the flanges, the breaker strip means including an anchor member secured to a facing member, the outer edge portion of the anchor member being formed with a surface diverging from the facing member and toward the outer edge to provide entry space for the outer flange, and means for connecting the breaker strip means to the inner flange, said diverging surface of the anchor member bearing against the inner side of the outer flange to assure engagement of the facing member against the outer side thereof.

3. In a refrigerator cabinet including inner and outer walls having inner and outer flanges, respectively, bounding the door opening, breaker strip means providing a connection between the flanges, the breaker strip means including an anchor member secured to a facing member, the outer edge portion of the anchor member being formed with a surface diverging from the facing member and toward the outer edge to provide entry space for the outer flange, and means for connecting the breaker strip means to the inner flange, said diverging surface of the anchor member bearing against the inner side of the outer flange to assure engagement of the facing member against the outer side thereof, said facing member being formed of a material which is substantially nonhygroscopic and has low conductivity for heat and said anchor member being formed of wood.

GREGG F. FORSTHOEFEL.
